Primary Examiner — Kendra Leslie Hamilton(74) *Attorney, Agent, or Firm* — Burr & Forman LLP(57) **CLAIM**

The ornamental design for a pacifier, as shown and described.

DESCRIPTION

FIG. 1 is a top, rear, left perspective view of a pacifier showing my new design;

FIG. 2 is a top, front, right perspective view thereof;

FIG. 3 is a bottom, rear, right perspective view thereof;

FIG. 4 is a bottom front, left perspective view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a front elevation view thereof; and,

FIG. 10 is a rear elevation view thereof.

The broken lines in the drawings depict portions of the pacifier that form no part of the claimed design.

1 Claim, 10 Drawing Sheets(56)
